UNITED STATES PATENT OFFICE.

LOUIS A. HOERR, OF ST. LOUIS, MISSOURI.

DESIGN FOR A DRAFT-LUG.

SPECIFICATION forming part of Design No. 32,998, dated July 24, 1900.

Application filed April 9, 1900. Serial No. 12,250. Term of patent 14 years.

To all whom it may concern:

Be it known that I, LOUIS A. HOERR, a citizen of the United States, residing at the city of St. Louis, in the State of Missouri, have invented and produced a new and original Design for a Draft-Lug, of which the following is such a full, clear, and exact description as will enable any one skilled in the art to which it appertains to make and use the same, reference being had to the accompanying drawings, forming part of this specification.

In the accompanying drawings, where my new and original design is shown and where like marks of reference refer to similar parts, Figure 1 is an isometric projection; and Fig. 2 is a similar view, but on a reduced scale and looking at the lug in a different position.

The leading features of my design are as follows: The body portion of the lug is composed of a top 5, bottom 6, sides 7, front end 8, and rear end 9. Extending from the sides 7 of the lug are projections 10. The body of the lug is substantially rectangular, except that the top 5 is provided with an inclined portion 11 forward of the projections 10. Formed in the top 5 is an opening 12 and in the bottom 6 a similar opening 13. Adjacent

to the opening 12 a web or flange 15 is formed on the top 5, and adjacent to the opening 13 a similar web or flange 16 is formed on the bottom 6. At the front part of the top 5 and forming a part of the front end 8 is a flange 17, and at the front part of the bottom 6 is a similar flange 18, also forming part of the front end 8. 19 is a web or flange which extends rearwardly from the web or flange 17, and 20 a flange which extends rearwardly from the web or flange 18. Formed in the front end 8 is a circular opening 21 and in the rear end 9 a similar circular opening 22. 23 are bolt-holes 40 which are formed in the sides 7.

Having fully described my invention, what I claim as new, and desire to secure by Letters Patent of the United States, is—

The design for a draft-lug substantially as shown and described.

In testimony whereof I have hereunto set my hand and seal in the presence of two subscribing witnesses.

LOUIS A. HOERR. [L. S.]
